UNITED STATES PATENT OFFICE

2,361,750

BOOSTER PUMP IMPELLER CONSTRUCTION

Theodore R. Dinsmore and Henry M. Taylor,
 Dayton, Ohio, assignors to Curtis Pump Company, Dayton, Ohio, a corporation of Ohio

Application February 10, 1943, Serial No. 475,348

7 Claims. (Cl. 103—113)

This invention relates to impeller constructions for pumps and more particularly to an impeller construction for a centrifugal type pump which construction increases the swirling of fluid being fed to the pumping vanes of the pump so as to decrease cavitation of the fluid at the pumping vanes.

In centrifugal type pumps the pumping vanes tend to shear the fluid being fed thereto and actually create cavitation in the fluid which materially decreases the efficiency and capacity of the pump. According to this invention the fluid to be pumped is caused to swirl before it reaches the pumping vanes so that the pumping vanes receive the fluid while it is swirling in the same direction as the vanes are being rotated. Because of this preliminary movement imparted to the fluid, the shearing effect of the pumping vanes on the fluid is materially decreased.

While the invention will hereinafter be specifically described as embodied in a centrifugal booster pump adapted to be attached to a gasoline tank, for receiving fluid gasoline directly therefrom, it should be understood that the principles of this invention are applicable to many other types of pumps and the illustrated and specifically described construction is intended only as an example of one form of the invention.

It is, then, an object of this invention to provide an impeller construction for pumps which imparts a swirling action to the fluid being fed to the pump for decreasing cavitation of the fluid at the pumping vanes.

Another object of this invention is to provide a simple attachment for impellers of centrifugal type pumps which will materially increase the efficiency and capacity of the pumps.

A still further object of the invention is to provide a device adapted to be mounted on or made integral with the impeller of a centrifugal type pump for swirling the liquid entering the pump.

A specific object of the invention is to provide an impeller construction for centrifugal type pumps including swirling vanes and pumping vanes, with the swirling vanes arranged to feed fluid in a direction substantially tangential to the pumping vanes.

A specific object of the invention is to provide an impeller construction for centrifugal type pumps including a disk member with upstanding curved pumping vanes defining pumping channels therebetween and a swirling vane attachment for said impeller having vanes extending in the direction of flow of fluid to the pumping channels from points in advance of the pumping vanes for

feeding the fluid to the pumping vanes substantially tangentially thereof.

Other and further objects of the invention will be apparent to those skilled in the art from the following detailed description of the annexed sheet of drawing which, by way of preferred example only, illustrates one embodiment of the invention.

On the drawing:

10 Figure 1 is an elevational view, with parts broken away and shown in vertical cross section, of a centrifugal type booster pump equipped with an impeller construction according to this invention.

15 Figure 2 is an enlarged top plan view, with a part in vertical cross section, of the impeller construction in the pump of Figure 1.

20 Figure 3 is a vertical cross-sectional view, with parts in elevation, taken along the line III—III of Figure 2.

25 Figure 4 is a bottom plan view of the swirling vane member included in the impeller construction of this invention.

As shown on the drawings:

30 25 In Figure 1 the reference numeral 10 designates generally an electric motor driven centrifugal type booster pump including a motor casing 11 having a head or cap 12 with a hollow neck portion 13 providing a shaft well, a pump casing portion 14 defining a volute chamber 15 and an annular flange 16 for attachment of the assembly to the bottom of a gasoline tank or the like.

35 The casing 14 has an open end 17 receiving a throat ring 18 defining a central inlet throat 19 to the volute chamber 15. An outlet conduit 20 communicates with the peripheral portion of the volute chamber 15 to receive the pumped fluid therefrom.

40 35 The throat ring 18 can be secured to the casing 14 by means of screws such as 21.

45 40 The motor in the casing 11 has a shaft 22 extending through the well provided by the neck portion 13. The shaft 22 has a reduced end portion or post 23 extending through the central portion of the casing 14 and through the throat 19 of the throat ring 18. A shoulder 24 is provided on the shaft at the base of the reduced portion 23 thereof.

50 45 As best shown in Figure 3, shims such as 25 can be mounted on the shoulder 24 for bottoming the hub 26 of an impeller disk 27. The hub 26 can be furcated as at 26b to receive tangs 28 on a seal member so that the seal member will be driven with the impeller. Since the seal construction

does not form part of the present invention it will not be further described.

The impeller disk 27 spans the inlet throat 19 and communicates at its outer periphery with the volute chamber 15 as shown in Figure 1.

The disk 27 has upstanding curved pumping vanes 29 around the periphery thereof. These vanes extend inwardly from the periphery of the disk but terminate at their inner ends substantially flush with the throat opening 19. The vanes 29 thus underlap the throat ring 18. The vanes extend into close proximity with the throat ring 18 and define therebetween pumping channels 30 for impelling liquid from the throat 19 to the volute chamber 15.

The hub 26 of the disk impeller 27 has an upwardly extending portion 26a also disposed around the post 23 providing a flared wall 31 in the inlet throat 19.

The top of this hub portion 26a is milled with a circular milling cutter to provide a key slot or groove 32 as best shown in Figure 3.

A swirling attachment member 33 composed of a sleeve 34 and four vanes 35 depending from this sleeve is mounted on the post 23 as shown in Figures 1 to 3 with the vanes 35 extending over the curved wall 31 of the hub portion 26a.

As best shown in Figure 4, the bottom of this attachment member 33 is cut with a circular milling cutter to provide a key slot or groove 36 therein. As shown in Figure 2, the top of the attachment member 33 is similarly cut to provide a key slot or groove 37 therein.

The sleeve portion 34 of the member 33 receives in the bottom groove 36 thereof the leg of a key 38 which leg also fits into the groove 32 on the hub portion 26a of the impeller disk 27.

The key member 38 has a foot portion seated in a groove 39 on the post 23. In this manner both the impeller disk 27 and the attachment member 33 are keyed to the post 23 and to each other. In order to provide proper operating clearance for the propeller disk in the pump casting 14 the groove 39 in the post 23 is elongated and shims mounted on the shoulder 24 will control the level of the assembly.

A propeller 40 composed of a hub portion 41 and a plurality of vanes 42 has the hub portion disposed around the upper end of the post 23 on top of the sleeve 34. Tangs 43 can be pressed down from the hub portion 41 into the groove 31 on top of the sleeve 34 for holding the propeller against rotation relative to the sleeve. A nut 44 is threaded onto the end of the post 23 for holding the impeller disk 27, the attachment member 33 and the propeller 40 on the post. The nut 44 can overlie the hub 41 of the propeller, for clamping the hub between the nut or a washer under the nut and the top of the sleeve 34.

As shown in Figure 1, the vanes 35 on the swirling attachment member 33 extend upwardly into the inlet throat 19 and flare outwardly over the curved wall 31 of the impeller disk 27 to overlie the base wall of the impeller disk.

As shown in Figure 2 these vanes 35 are preferably disposed between the pumping vanes 29 on the disk 27 so as to lie at about the midpoint of every other pumping channel 30. As illustrated in Figure 2, eight pumping channels 30 are provided and four swirling vanes 35 are provided. Since the vanes 35 are driven in the same direction as the vanes 29, and since the same terminate inwardly of the vanes 29 at points in-

termidiate the vanes, fluid entering the throat 19 will be swirled or rotated by the vanes 35 before it reaches the vanes 29. The swirling mass of fluid will be directed by the vanes 35 and outwardly flared walls 31 of the hub 26a in a radially outward direction so that, when it hits the vanes 29, it is already moving in the direction of liquid in the pumping channels 30. As a result the inner edges of the vanes 29 do not have as much shear effect on the liquid and less cavitation will occur at the pumping vanes. Because of decreased cavitation, the pumps will have a higher capacity and will operate much more efficiently.

15 The propeller 40 is useful in creating a lateral flow of liquid adjacent the inlet throat 19 for the purpose of throwing out bubbles of gases and vapors entrapped in the liquid being fed to the pump. Because of elimination of these gases, cavitation at the pumping vanes is further decreased and the pump has an even greater efficiency.

Liquid is usually fed to the inlet throat 19 by gravity flow from a container such as a gasoline tank. The swirling attachment member 33 of this invention will make possible increased delivery capacity of the pump at lower liquid levels above the level of the inlet throat 19 than was heretofore possible.

20 From the above descriptions it will be understood that this invention provides an impeller construction especially adapted for centrifugal type pumps which construction swirls fluid such as liquid being fed to the pump for feeding the fluid to the pumping vanes as a moving or swirling mass to decrease cavitation of the fluid at the pumping vanes.

25 It will, of course, be understood that various details of construction may be varied through a wide range without departing from the principles of this invention and it is, therefore, not for the purpose to limit the patent granted hereon otherwise than necessitated by the scope of the appended claims.

30 We claim as our invention:

1. A pump impeller construction comprising a flat disk, a plurality of elongated spaced pumping vanes on one face of said disk around the outer marginal portion thereof, and a plurality of 35 additional vanes radiating from the central portion of said disk and extending from a level above the pumping vanes to the spaces between the pumping vanes for swirling liquid being fed to the pumping vanes.

40 2. An impeller construction for a centrifugal type pump having a central inlet and a peripheral outlet which comprises a plurality of spaced radiating pumping vanes defining pumping channels therebetween for receiving liquid from said central inlet to discharge the liquid by centrifugal force to said peripheral outlet, and a plurality of additional vanes extending from the spaces between the pumping vanes into said central inlet for swirling the liquid before it reaches the pumping vanes.

45 3. In a centrifugal type pump having a central fluid inlet and a peripheral pumping chamber, the improvement which comprises an impeller disk spanning said inlet and communicating around the periphery thereof with said pumping chamber, upstanding pumping vanes on said disk extending from the periphery of the disk into spaced relation from the center of the disk, and a plurality of additional vanes radially inward of said pumping vanes extending into said

central inlet for swirling fluid passing therethrough to said pumping vanes.

4. A swirling device for a centrifugal type pump which comprises a sleeve member adapted to be disposed over a drive shaft, and a plurality of vanes extending radially around the sleeve and depending from said sleeve member at spaced intervals therearound.

5. An impeller construction comprising a disk having an upstanding hub portion, a plurality of upstanding spaced pumping vanes on said disk extending inwardly from the periphery of the disk and terminating in spaced relation from the upstanding hub portion, and a plurality of radial vanes around said hub portion extending from a level above the tops of the pumping vanes to points adjacent the spaces between the pumping vanes.

6. In a centrifugal type pump having a central inlet throat and a peripheral outlet, the improve-

ments of an impeller disk inwardly from the throat spanning the throat opening and communicating around the periphery thereof with said outlet, upstanding pumping vanes on said disk defining pumping channels from the throat opening to the outlet, and additional vanes extending from points adjacent the inner ends of said channels into said throat.

7. An impeller construction for centrifugal type pumps comprising a disk member having a plurality of spaced pumping vanes therearound on one face thereof, and a plurality of upstanding vanes radiating from the central portion of said member between the pumping vanes and adapted to swirl liquid being fed to the pumping vanes for feeding said liquid tangentially to the pumping vanes.
